UNITED STATES PATENT OFFICE.

PHILIP LANGE, OF PITTSBURG, PENNSYLVANIA, ASSIGNOR TO GEORGE WESTINGHOUSE, JR., OF SAME PLACE.

ELECTRIC SWITCH.

SPECIFICATION forming part of Letters Patent No. 366,407, dated July 12, 1887.

Application filed December 2, 1886. Serial No. 220,443. (No model.)

To all whom it may concern:

Be it known that I, PHILIP LANGE, a subject of the Emperor of Germany, residing in Pittsburgh, in the county of Allegheny and 5 State of Pennsylvania, have invented certain new and useful Improvements in Electric Switches, of which the following is a specification.

The invention relates to apparatus employed for altering or controlling the connections of an electric circuit.

The object of the invention is to provide a switch whereby the connections may be made and interrupted by a sudden and very considerable movement of the circuit-closing arm, thereby preventing the formation of an electric arc across the contact-points when the circuit is broken.

In the accompanying drawings, Figures 1 20 and 2 are elevations, partly in section, of a device embodying the features of the invention. Fig. 3 is a plan view of the same.

Referring to the drawings, A represents a suitable inclosing case. Within this case 25 there is placed a cylindrical box, B, containing the circuit-controlling mechanism. A shaft, C, carrying an operating-handle, C', extends through the case and into the box B. This shaft carries a metal cross-bar, D, the 30 opposite ends of which rest upon two inclined or cam-shaped surfaces, E and E'. The cross-bar is vertically movable along a square portion of the shaft C. The cams E' and E' rise gradually from the base E and terminate at 35 their upper ends in vertical shoulders e' e'. When the cross-bar D is turned by the handle C', it is pressed upward gradually by the cam-surfaces against the force of a spring, F, surrounding the shaft, until it reaches the 40 vertical shoulders e' e', whereupon it escapes and is forced downward suddenly by the recoil of said spring. One of the arms of the cross-bar D carries a finger or pin, G, which, when the cross-bar is driven downward, strikes 45 one end or the other, H' or H'', of a tilting lever, H. This lever carries a circuit-closing arm, K, which is caused to enter between two contact-springs, K' and K'', when the pin G strikes the end H'' of the lever H. This will 50 occur at the time when the end of the arm D,

carrying the pin G, falls over the vertical shoulder e''. By turning the handle C' half around in the same direction, the pin G will again be gradually raised, and by falling suddenly over the shoulder e', it will strike the 55 end H' of the lever H and tilt the same in the opposite direction, thereby suddenly separating the arm K from the springs K' and K''.

For the purpose of holding the lever H in one or the other of its alternate positions until 60 it is forcibly removed therefrom, the contact-springs K' and K'' may, with advantage, be curved toward each other, as indicated in the drawings, and these, by virtue of their resiliency, will thus grasp the arm K on opposite 65 sides and hold it until forcibly removed therefrom. A curved flat spring, M, bearing against the other end of the arm H, serves to hold the lever with the arm K away from the contact-springs. 70

I claim as my invention—

1. The combination, substantially as described, of a rotating cross-bar, two cams bearing against the opposite arms of the same, a tilting lever, a spring tending to force said 75 cross-arm toward said lever, a contact device carried by said lever, and contact-springs between which said arm is made to pass.

2. The combination of a rotating shaft, an arm carried thereby, a detached circuit-controlling lever actuated by said arm, and an independent stationary cam, against which 80 said arm bears and from which it is suddenly released when said shaft is in a predetermined angular position.

3. A circuit-controlling device consisting of a rotating-shaft, a cross-bar free to move longitudinally along said shaft, one or more cams terminating in vertical faces, a circuit-controlling lever, and electrical contacts applied 85 to said lever.

4. The combination of the shaft C, the cross-bar D, longitudinally movable along said shaft, the spring F, the double cam E' E'', the tilting lever H, the pin G, carried by the 95 cross-bar D and impinging upon one end or the other of the lever, according to the angular position of the shaft C, and the electrical contacts controlled thereby.

5. In an electric switch or circuit-closer, the 100

combination, with a lever or circuit-closing arm, of a revolving cross-bar tilting the same, one or more cams for holding said arm away from said lever, except when the arm is in 5 one or the other of two predetermined angular positions, and means for thereupon forcing the arm against one end or the other of said lever, substantially as set forth.

In testimony whereof I have hereunto subscribed my name this 4th day of November, 10 A. D. 1886.

PHILIP LANGE.
